United States Patent Office.

FREDERICK LADNER, OF PHILADELPHIA, PENNSYLVANIA, ASSIGNOR TO
LADNER & BIRD, OF SAME PLACE.

Design No. 4,707, dated March 14, 1871.

DESIGN FOR THE ORNAMENTATION OF GLASS-WARE.

The Schedule referred to in these Letters Patent and making part of the same.

I, FREDERICK LADNER, of the city of Philadelphia, in the State of Pennsylvania, have invented and produced a new and original Design for the Ornamentation of Glass-Ware, of which the following is a specification.

The nature of my design is fully represented in the accompanying drawing, to which reference is made.

It consists of the crossed rifles or fire-arms *a a*, target *b*, on a frosted shield, *c*, having a smooth portion, *c'*, for the subsequent application of letters or numbers, all produced or impressed in molding the

glass-ware upon which said ornamental design is required.

Claim.

I claim as my invention—

The design for the ornamentation of glass-ware, substantially as shown and described.

FREDK. LADNER.
